(57) **CLAIM**

The ornamental design of a threshold end attachment set, as shown and described.

DESCRIPTION

FIG. 1 is a perspective view of a threshold end attachment

for one end of a threshold end attachment set and showing my new design;

FIG. 2 is a top view thereof;

FIG. 3 is one side view thereof;

FIG. 4 is bottom view thereof;

FIG. 5 is a front view thereof;

FIG. 6 is a rear view thereof;

FIG. 7 is an opposite side view thereof;

FIG. 8 is a perspective view of a threshold end attachment for the opposite end of the threshold end attachment set;

FIG. 9 is a top view of the threshold end attachment shown in FIG. 8;

FIG. 10 is a side view of the threshold end attachment shown in FIG. 8;

FIG. 11 is a bottom view of the threshold end attachment shown in FIG. 8;

FIG. 12 is a rear view of the threshold end attachment shown in FIG. 8;

FIG. 13 is a front view of the threshold end attachment shown in FIG. 8; and,

FIG. 14 is an opposite side view of the threshold end attachment set shown in FIG. 8.
